UNITED STATES PATENT OFFICE

2,609,869

AIR ADMISSION DIRECTOR FOR OIL BURNERS

Thomas W. Murphy and James M. Carroll, Narberth, Pa., assignors to Monarch Manufacturing Works, Inc., Philadelphia, Pa., a corporation of Delaware

Application December 21, 1950, Serial No. 201,916

2 Claims. (Cl. 158—76)

2

Figure 5 is an elevation looking at the right-hand side of Figure 4; and

Figure 6 is an elevation looking at the left-hand side of Figure 4.

5 A conventional oil burner air tube is indicated at 2 to which air is supplied by means of the fan or blower 4. A conventional locking arrangement at the rear of the air tube indicated at 6 supports the oil feed line 8 which terminates in a nozzle 10 of conventional construction.

10 A cone ring 12 is secured within the end of the air tube by screws 14 and is provided with a smoothly curved converging inner surface 16 which forms an angle with the opening 18. With 15 the construction about to be described, the cone ring should have a smooth inner surface of rotation, such as indicated at 16, without vanes.

15 A spider indicated at 20 is secured to the oil pipe 8 by means of a set screw and is provided 20 with a pair of arms 22 which are bored to provide a mounting for the insulating tubes 24, which are clamped therein and which support the ignition electrodes 26.

25 A second pair of arms of the spider indicated at 28 serve for the mounting of the stabilizer assembly to the oil tube, the mounting being afforded by means of bolts passing through the ends of the spider arms and the assembly with interposed spacers 30.

30 The stabilizer assembly is particularly illustrated in detail in Figures 4, 5 and 6. It comprises a plate 32 which is stamped to provide outer blades 34 which are twisted to form helicoidal vanes for imparting spin to the air, and 35 also stamped to provide an inner series of blades indicated at 38 which are so arranged as to impart spin to air passing between them in a sense opposite to the spin imparted by the blades 34. Surrounding the blades 38 there is a generally 40 cylindrical short tube indicated at 40, and is provided with a flange 42 riveted to the plate 32. Within a central opening in the plate 32 there is secured by means of a flange a tubular member 44 provided with a bore 46 for the reception of 45 the body 48 of the nozzle 10. As will be evident from Figure 4, there is provided by the members 44 and 40 an annular space into which there is discharged the air passing through the blades 38. In particular, the member 40 provides a barrier 50 between the flows passing through the blades 34 and the blades 38, respectively. The plate 32 is provided with openings 50 for the passage of the insulating tubes 24 and the flange 42 is notched as indicated to clear these tubes. As will be 55 noted, the insulating tubes terminate substan-

This invention relates to oil burners and has particular reference to the equipment for directing and stabilizing the air in the blast tube of conventional gum type oil burners.

The general object of the present invention is to provide stabilizing equipment of simple and inexpensive construction, particularly designed for oil burners of low capacity, such as those for domestic use, though the invention may equally well be applied to oil burners of larger capacity.

The principal object of the invention is to balance the air delivered by the fan supplying the air for combustion so as to produce high CO₂ content of the flue gases with a clean flame.

Another object is to so stabilize the air delivered to the sprayed oil that the flame produced by a present day smaller capacity nozzle, handling for example about one-half gallon of oil per hour, will not be extinguished even though the full volume from the fan is delivered to the stabilizing equipment, when the fan and same stabilizing equipment is normally capable of delivering sufficient air for combustion of at least two gallons of oil per hour, which is the critical test of proper air balance. The air balance is obtained by having the combustion air delivered to the stabilizing equipment under relatively high static pressure, with the stabilizer so constructed as to direct the greater volume of air spirally and peripherally of the stabilizer and with a lesser volume of air directed substantially centrally of the first mentioned air volume but in counter current to the peripheral air volume, and in such controlled proportion that the two forwardly moving swirling columns of air will converge rearward of the converging cone ring and be delivered therethrough with sprayed oil for combustion.

The foregoing indicated objects as well as those particularly relating to details of construction and operation will become apparent from the following description read in conjunction with the accompanying drawings, in which:

Figure 1 is an axial section through a burner embodying the invention showing the stabilizer and associated parts in side elevation;

Figure 2 is an end elevation looking at the exit end of the cone ring;

Figure 3 is a vertical section taken on the plane the trace of which is indicated at 3—3 in Figure 1;

Figure 4 is a side elevation, partly in section, showing in particular details of the stabilizer assembly;

tially coextensively with the outer end of the member 40.

The arrangement just described provides inner and outer currents of air which are reversely rotating and which provide the proper flow to secure maximum efficiency of combustion.

The mechanical construction of the stabilizer assembly is not only inexpensive but quite rigid and it will be noted that the outer ends of the blades 34 lie in a cylindrical surface which is only slightly less in diameter than the inner diameter of the air tube thus providing a support for the nozzle end of the oil feed line to maintain the nozzle in accurate axial alignment with the air tube and the outlet 18.

What is claimed is:

1. A stabilizer assembly for an oil burner comprising a sheet metal plate, said plate having its periphery formed and shaped to provide an outer annular array of substantially helicoidal sheet metal vanes to impart rotation to air flowing therebetween, having an inner portion formed and shaped to provide an inner annular array of substantially helicoidal sheet metal vanes to impart rotation to air flowing therebetween in a direction opposite to that imparted by the outer vanes, having an annular blank portion separating the two vaned annular portions and provided with openings for the passage of insulating tubes for ignition electrodes, and having a blank portion within the inner vanes provided with a central opening for the passage of a fuel nozzle assembly, and a substantially cylindrical member extending axially of the plate from the blank annular portion thereof in the direction of air flow to provide a barrier separating the oppositely rotating air flows.

2. A stabilizer assembly for an oil burner comprising a sheet metal plate, said plate having its

periphery formed and shaped to provide an outer annular array of substantially helicoidal sheet metal vanes to impart rotation to air flowing therebetween, having an inner portion formed and shaped to provide an inner annular array of substantially helicoidal sheet metal vanes to impart rotation to air flowing therebetween in a direction opposite to that imparted by the outer vanes, having an annular blank portion separating the two vaned annular portions and provided with openings for the passage of insulating tubes for ignition electrodes, and having a blank portion within the inner vanes provided with a central opening for the passage of a fuel nozzle assembly, and a substantially cylindrical member extending axially of the plate from the blank annular portion thereof radially inwardly of the ignition electrode openings therein and in the direction of air flow for an axial distance equal to less than the diameter of the stabilizer assembly to provide a barrier separating the oppositely rotating air flows.
